(57) **CLAIM**

We claim the ornamental design for the razor cartridge, as shown and described.

DESCRIPTION

FIG. 1 is a top isometric view of the razor cartridge.

FIG. 2 is a bottom isometric view of the razor cartridge.

FIG. 3 is a bottom view of the razor cartridge.

FIG. 4 is a plan view of the razor cartridge.

FIG. 5 is a back view of FIG. 4.

FIG. 6 is a front view of FIG. 4.

FIG. 7 is a left side view of FIG. 4; and,

FIG. 8 is a right side view of FIG. 4.

The broken lines are shown for illustrative purposes only and form no part of the claimed design.

The broken lines shown in the accompanying drawings show environmental structure and are for illustrative purposes only and form no part of the claimed design.
